UNITED STATES PATENT OFFICE.

CLYDE W. McCABE, OF ANTWERP, OHIO.

CORN-PLANTER.

No. 800,468.

Specification of Letters Patent.

Patented Sept. 26, 1905.

Application filed November 1, 1904. Serial No. 230,962.

To all whom it may concern:

Be it known that I, CLYDE W. McCABE, a citizen of the United States, residing at Antwerp, in the county of Paulding and State of Ohio, have invented new and useful Improvements in Corn-Planters, of which the following is a specification.

My invention relates to improvements in planters of that class or kind especially adapted for dropping seeds at determined distances apart, particularly for depositing corn; and the primary object is to provide a machine of the kind named and for the purposes intended which is of simplified construction, efficient in operation, and durable in use.

Further objects of the invention are, first, to provide a novel form of marking apparatus which is normally out of operation and which can be thrown into operation at any time and which is designed to carry any kind of marking material, such as fertilizer, and, second, to provide a marking apparatus which may be used as a fertilizer-distributer.

A further object of the invention is to provide a planter with a movable frame whereby the seed-droppers and marking apparatus may be brought into alinement with markings at each end of the row.

With these objects in view the invention consists in the novel construction of parts and their aggroupment in operative combination, as will be hereinafter fully specified and then the novelty asserted particularly pointed out and distinctly claimed.

I have fully and clearly illustrated the improvements in the annexed drawings, to be taken as a part of this specification, and reference being thereto had—

Figure 1 is a top plan view of the complete machine. Fig. 2 is a longitudinal section on the line 2 2 of Fig. 1. Fig. 3 is a longitudinal vertical section on the line 3 3 of Fig. 1. Fig. 4 is a central vertical section through one of the hoppers and indicating the means for operating the feed-slides. This view is taken on the line 4 4 of Fig. 1, and Fig. 5 is a vertical central section through the driving-sprocket mounted on the axle and showing the means for holding the sprocket fast to the axle.

In the drawings the same parts appearing in different illustrations are designated by similar reference notations, and reference being made to the drawings, A A designate the ground or driving wheels, the hubs of which are made fast to an axle 1. On the axle are

arranged oppositely-placed bearings 2, one only being shown, which carry and are secured to the rear portion of a rectangular frame B, composed of side bars 3 4 and end bars 5. The side bars 3 4 are provided with longitudinal slots 6, alining with each other, wherein the supporting-stirrups of a transversely-disposed frame C are hung, as hereinafter specified.

The tongue 7 is positioned and secured longitudinally in the middle of the frame B and extends rearward, as shown, and has its rear end firmly connected to the side rail 3 by a bar 8. To the under side of the tongue is fixed a keeper-bar 9, which supports the transversely-disposed frame and prevents it from swinging down on the stirrups.

C designates a rectangular frame composed of side rails 10 11 and end pieces 12, the frame being disposed at right angles to the frame B, as shown in Fig. 1 of the drawings, and is supported by stirrups or clips 13, slidably hung in the slots 6 of the side rails of the frame B. The frame C is held against swinging downward by the keeper-bar 9, on which it rests at its middle, to bring the seed-spouts and marking apparatus into alinement with the markings at the ends of each row, whereby the movements of the whole machine to accomplish this is obviated. By mounting the frame for sliding movement said frame may be properly adjusted. To accomplish the adjustment of the frame C, a link or arm 14 has one end pivotally connected to the side bar 10 of the frame C and has its other end pivotally connected to the lower end of the lever 15, fulcrumed to a hanger or bracket 16, secured to the rear portion of the tongue. To hold the lever 15 in adjusted position, it is provided with a suitable hand-pawl 17, the end of which engages in a sector-rack 18, secured to the rear part of the tongue, substantially as seen in the drawings. The frame C supports the members making up the seed-dropping and the marking-can devices and also supports the mechanism for operating those devices.

On the axle 1 is loosely mounted a driving sprocket-gear 19, made to turn with the axle by means of a fixed radial arm 20 projecting from the axle and provided with an aperture in its free end, wherein is detachably inserted a pin 21, which engages in pin-holes 22, made in the body of the driving sprocket-gear. The connection of the pin with the sprocket is made by pushing the sprocket onto the pin,

where it is held engaged by frictional contact. In suitable hangers 23, secured to and depending from the ends of the frame C, is journaled a rock-bar shaft 24. Adjacent to 5 each end of the rock-bar 24 is loosely mounted thereon a clutch member 25, provided with an upwardly-extending arm 26, provided at its upper end with a slot 27, for the purpose hereinafter stated. The other member 28 of 10 the clutch is slidably mounted on the rock-bar and is thrown in and out of engagement with the members 25 by means of elbow-levers 29, fulcrumed to the frame-bar 10, as seen at 30, and their long arms carried parallel with the 15 frame-bar 10 and at their free ends have pivotally secured thereto sliding rods 31, mounted in brackets 33, carried by a bar 36, secured to the rails of the frame C. The rods 31 are provided with foot-plates 34, and to position the foot- 20 plate of the rod 32 out of the way of the chain 41 said rod is bent laterally, as at 35. The clutches serve to control the operation of the marking-can slides and are brought into engagement only when required to move the slides to 25 discharge the marking material from the cans, particularly for a distance at the ends of the rows, and then they are thrown out of engagement with the slides in closed position and so remain until brought into action again by the reengagement of the clutches. Springs are positioned 30 between the advance brackets 33 and collars 35^a, rigidly secured, and serve to normally retain the clutches out of operative position, and said clutches are adjusted to be brought 35 into operative position by a forward pressure brought to bear upon the foot-plates 34. To permit the clutch members 28 to rock with the rock-bar, the short arms of the clutch-levers are provided with suitable slots 28^a, in 40 which the pins in the slideable clutch members loosely engage, as indicated in the drawings.

37 designates a double inclined or arched bar having its ends supported on and secured to the rails 10 11 and at its apex is provided 45 with a bearing 38, wherein is journaled a stud-shaft 39, whereon is mounted a sprocket-wheel 40, carrying a sprocket-chain 41, extending from the driving-sprocket 19. The sprocket-wheel 40 is provided with laterally- 50 extending pins 42, which engage against a vertically-extending arm 43, fixed in the rock-bar 24 in the path of the pins 42. It will be seen that this tripping mechanism eventuates in 55 rocking the rock-bar, and at each engagement of the contacting parts the bar is rocked, and through its connections hereinafter described the seed and marking devices are thus operated.

44 designates the oppositely-disposed marking-cans of duplicate construction made in 60 such capacity as will fit them for the purposes desired and consisting of cylindrical bodies and funnel-shaped bottoms opening into a discharge-tube 45. In the base of each of the 65 marking-cans is made a slideway or slot where-

in is disposed a sliding plate 46, the outer end of which is pivotally connected to the upper end of the arm 26 by a pin 47 projected through the slot 27. To the slide 46 at a lower parallel plane is a second slide-plate 48, 70 arranged through a slideway provided in the stem of the holding-can, substantially as seen in Fig. 4 of the drawings. In the slides 46 and 48 are made apertures 49 50, so positioned that when the aperture 49 is opened the aperture 50 is moved from the bore of the stem and the bore is closed by the plate 48, and when the plate 46 is moved to bring the aperture 49 in registration with the bore of the stem the aperture 50 will register with the bore of the stem, and the plate 46 will close the stem above it, as seen in Fig. 4 of the drawings. It will thus be seen that the space between the plate or slides measures the quantity of material which is discharged from the holding-cans at one time. As heretofore stated, the engagement of the clutch members operates these slides.

51 designates the seed-hoppers made in the usual tapering form and of such capacity as 90 may be required to suit the machine to the uses of its work. In the bottom of the seed-hoppers are made apertures, which are intermittently opened and closed by an apertured disk 52, formed with perimetral projections 95 or teeth 53. The disk is pivotally disposed on a support positioned in the bottom of the seed-hopper, as indicated in Fig. 1 of the drawings. Below the seed-hopper is arranged a seed-spout 54, having its lower end suitably 100 secured in the heel of the row or furrow-openers 55 in any suitable manner. The furrow-openers 55 are of the usual shape, substantially as seen in the drawings, and have the upper ends of the runners pivotally fastened 105 to the side bar or rail 11 of the frame C, as shown at 56 in Figs. 1 and 3.

On the rock-bar 24 are formed or secured upwardly-extending arms 57, having slot-bearings in their upper ends, in which the 110 outer ends of reciprocable bars 58, which are projected through the wall of the seed-hoppers are so arranged that their free ends engage against the projections of the disks 52, to which the reciprocations of the bars 58 give 115 an intermittent rotation.

In order to adjust the tension of the chain 41, a stud-shaft 59' is fixed in the bar of the lever 15, and mounted thereon is a sleeve or pulley 59, on which the chain rides. It will 120 be seen that when the lever is operated to move the frame C the pulley 59 automatically adjusts the tension of the chain to the adjusted position to which the frame may be moved.

A spring 60, having one end secured to the side rail 11 of the frame C and the other end fastened to the trip-arm 43, serves to hold the trip-arm in proper position against the action of the pins in the sprocket-wheel 40, as indicated in Fig. 2 of the drawings.

A suitable seat 61 is supported at the rear end of the frame B. The functions of the several elements and coacting members have been specified in the description; but the general operation of the machine may be rehearsed as follows: The driving-sprocket is made fast to the axle, which, through the medium of the chain, communicates rotation to the sprocket-wheel 40, bringing the pins therein into sequential contact with the trip-arm 43 of the rack-bar 24, causing that element to rock in its bearings, which movement reciprocates the bars 58 and intermittently rotates the seed-disks 52, and thus discharge the seeds into the furrows made by the furrow-openers. The marking apparatus is used upon nearing the end of a row, and it is controlled by the operator in the manner hereinbefore pointed out, and as each clutch mechanism may be operated independently either one or both of the marking devices may be thrown into operation at the will of the operator. It is apparent that the marking apparatus may be used to distribute fertilizer as well as to distribute a marking material.

Having thus described the invention, what is claimed as new is—

1. In a corn-planter, a supporting-frame, a transversely-disposed frame slidably swung to the supporting-frame, a wheeled axle, a driving sprocket-wheel on the axle, a sprocket-wheel provided with laterally-extending pins and mounted on the slidable frame, a chain connecting the sprocket-wheels, a rock-bar carried by the slidable frame provided with upwardly-extending arms, and a vertically-extending arm engaged by the pins of the sprocket-wheel, seedboxes mounted on the slidable frame provided with seed-openings in their bottoms, rotatable disks in the seed-boxes provided with seed-openings and teeth on their perimeters, a slidable bar having one end pivotally connected to the upwardly-extending arms of the rock-bar and adapted to engage the teeth of the disks and actuate the seed-disks, means to intermittently rock the rock-bar.

2. In a corn-planter, a supporting-frame, a transversely-disposed frame slidably swung to the supporting-frame, a wheeled axle, a driving sprocket-wheel on the axle, a sprocket-wheel provided with laterally-extending pins and mounted on the slidable frame, a chain

connecting the sprocket-wheels, a rock-bar carried by the slidable frame provided with upwardly-extending arms and a vertically-extending trip-arm engaged by the pins of the sprocket-wheel, seedboxes mounted on the slidable frame provided with seed-openings in their bottoms, rotatable disks in the seed-boxes provided with seed-openings and teeth on their perimeters, a slidable bar having one end pivotally connected to the upwardly-extending arms of the rock-bar and adapted to engage the teeth of the disks and actuate the seed-disks, means to intermittently rock the bar, and means to adjust and lock the slidable frame in position.

3. In a corn-planter, a supporting-frame, a transversely-disposed frame slidably swung to the supporting-frame, a wheeled axle, a driving sprocket-wheel on the axle, a sprocket-wheel provided with laterally-extending pins and mounted on the slidable frame, a chain connecting the sprocket-wheels, a rock-bar carried by the slidable frame provided with upwardly-extending arms and a vertically-extending trip-arm engaged by the pins of the sprocket-wheel, seedboxes mounted on the slidable frame provided with seed-openings in their bottoms, rotatable disks in the seed-boxes provided with seed-openings and teeth on their perimeters, a slidable bar having one end pivotally connected to the upwardly-extending arms of the rock-bar and adapted to engage the teeth of the disks and actuate the seed-disks, means to intermittently rock the bar, means to adjust and lock the slidable frame in position, fluid-marking cans mounted on the slidable frame, slides to control the advent of the marking fluid therefrom, and arms on the rock-bar to actuate the slides.

4. In a corn-planter, the combination with the wheeled axle, of a driving sprocket-wheel on the axle, a sprocket-wheel to intermittently actuate the seed mechanism, a chain on the sprocket-wheels, a lever, and a pulley carried by the lever and arranged to engage the chain.

In testimony whereof I affix my signature in presence of two witnesses.

CLYDE W. McCABE.
